CURVED-EDGE WINDOW ORGANIZATION

Trygve Vigmostad, Detroit, Mich., assignor to
The Murray Corporation of America, a corpora-
tion of Delaware

Application December 8, 1930. Serial No. 500,695

5 Claims. (Cl. 296—48)

Use being currently made of inclined windshields, as favorable to an avoidance of glare and to other useful effects, corresponding efforts are naturally made to minimize the diameter of 5 windshield frame or post elements adjacent forward edges of car doors and the diameter of door elements serving as frames for window openings therein; and it is an object of the present invention to provide, for use in such doors, a window 10 having a curved leading edge and provided with a substantially arcuate or suitably curved guide therefor;—said edge and said guide being so disposed as substantially or entirely to obviate uncovering of any portion of said edge opposite a 15 slightly acute but rounded angle provided at the lower front corner of the window opening.

In preferred embodiments of the invention, a rearward edge of the mentioned window being optionally provided with a curvature substantially parallel with or generally similar to that 20 of the mentioned leading edge, and the top and bottom edges of said window being preferably substantially horizontal and parallel, a double-arm regulator of a known type may be so employed as to maintain the horizontality of the 25 mentioned top and bottom edges during a raising and lowering of said window while nevertheless permitting said window to freely respond to the guidance of the suitably curved channel element,—adapted respectively to receive the leading 30 and the rearward edge of said window and to cam the window forward and back during lowering and raising movements thereof.

Other objects of the present invention, in which 35 use may be made of guides which comprise resilient portions, and/or which have but limited and/or varying areas or lines of cooperative engagement with the mentioned window edges, may be best appreciated from the following description 40 of an illustrative embodiment of the invention, taken in connection with the appended claims and the accompanying drawing.

Fig. 1 may be referred to as an inside elevational view of a right-hand door of an automotive vehicle, parts being broken away and 45 cooperating members being omitted.

Fig. 2 is a horizontal sectional detail view, taken substantially as indicated by the line 2—2 of Fig. 1.

Referring first to general features, the illustrated door comprises an outside panel 10 and an outside panel 11, extending substantially parallel with one another and secured together by Z-section frame elements 12 of a known type; and the 50 mentioned parts may be said to cooperate in the

provision of a sash or frame for a substantially trapezoidal window opening. The latter includes, in addition to an inclined leading edge 13 (shown as deviating less from perpendicularity than does the corresponding edge portion 14a of the leading 60 edge of said door), a rearward edge 15, and substantially horizontal top and bottom edges 16 and 17. A rearward edge 18 of said door being shown as substantially vertical, as seen in elevation, a portion 14a of the mentioned leading edge is 65 shown as meeting a lower portion 14b of said edge in an obtuse angle 14. This is shown as adjacent a slightly acute but rounded angle formed between the edges 13 and 17 of the window opening; and the problem to which the present invention is directed may be understood to relate to an avoidance of an uncovering of any portion, or of any considerable portion, of the edge 13, in the region of this angle, or any uncovering of a forwardly curved leading edge 13' 70 of a window 19, movable relatively to said opening. The window 19 may be raised and lowered by means of a double-arm regulator 20, of a known type, adapted to maintain the horizontality of top and bottom edges 16' and 17' of said window while permitting a limited advance and retraction thereof under the control of special guidance means including a suitably curved guide 75 or guides.

Drawn as a chord relatively to a curved forward 80 guide 21, a dot-and-dash comparison line 22 is shown as extending between the position occupied by an upper front corner of the window 19, when closed, and the position occupied by a lower front corner of said window when open; and it will be seen that an elimination of mentioned 85 curvatures and a guidance of the window 19 in a path parallel with the line 22 (as, by a straight channel element similarly extending across an angle in the forward edge of the door) would 90 tend to expose at least a portion of the edge 13' in the region of the upper front corner of the window 19, whenever said window is lowered to or below a position such as that in which it is shown in full lines. To obviate this effect, a portion 95 of the forward edge 13', between the mentioned forward corners, is given a forward concavity sufficient to enable the window 19 at all times to overlap the edge 13 even in the region of the angle formed between said edge and the edge 17; and the guide 21, preferably serving as a cam, may be given, at least in the central portion thereof, a forward curvature suitable to the 100 effect here referred to.

To obviate exposure of the upper portion of a

- rearward edge 15' of the window 19 upon a lowering of said window from a position in which its top edge occupies the level indicated by the line 16" through a position indicated by line 16' and line 17" and to a position indicated by the line 17", the edge 15' may advantageously have a curvature generally similar to that of the edge 13'; and the edge 15' may advantageously be received in one or more guides curved similarly to
- 10 the mentioned guide 21, at least in the central portion thereof. Neither an exact concentricity or an exact parallelism of curvatures in guides for the edges 13' and 15' of the window 19 would be entirely favorable to the indicated mode of
- 15 operation in case the guides were entirely rigid throughout the length thereof and the edges 13 and 15 were in continuous engagement with the bottom thereof; and even though a central portion of the guide 21 be somewhat rigidly supported (as by the contact with the Z-section ele- 20 ment 12 and/or a suitable bracket or brackets 23, 24) terminal portions 21a, 21b of the guide 21 may advantageously be so resilient or so sup- 25 ported as to permit a limited deformation of at least the bottoms thereof incidentally to the rais- 30 ing and lowering of the window 19. An analogous construction may be employed in the case of a rear guide 25 comprising resilient or other ter- 35 minal section 25a, 25b and shaped to receive the rearward window edge 15'—brackets 26 and 27 being shown as securing the last mentioned guide at two levels only.
- Loosely referring to the curved lines provided by edge 13' and guide 21 as "arcs" and to the dot-and-dash line 22 as a "chord", it will be seen that the center of said chord may fall substantially at the level of the forward extremity of the rounded angle between edges 13 and 17,—the exact curvature of any prominence provided by edge 13' being dependent upon the angle referred to and/or that obtuse angle in the forward edge of the car door across which the chord 22 extends; and, as to mode of operation, it will be understood that manipulation of an inwardly exposed crank 28 of
- 45 the double-arm regulator 20 is effective, by engagement of cam fingers 29 within a horizontal slot 30 in a glass-receiving connection element 31 adjacent the lower edge 17' of the window 19, to raise and lower said window in a manner per- 50 mitting the latter to "float" in a fore-and-aft di- 55 rection and under the control of guidance means such as provided by the channels 21 and 25, parts thereof serving as cams; and that the curvatures and resilient properties of said channels, where 55 cooperating with curved prominences in edges 13' and 15' of the window 19, are such as to obviate or minimize any uncovering of the last-mentioned edges incidentally to the raising and lowering of said window.
- 60 Although the foregoing description has included complete details of but one embodiment of the present invention, it should be understood

not only that various features thereof might be independently employed but also that numerous modifications, additional to any suggested herein, might easily be devised by skilled workers, if informed of the foregoing,—all without departure from the scope of the present invention, as the latter is indicated above and in the following claims.

What I claim is:

1. In a window organization for a car door 85 whose forward end includes an obtuse angle be- 90 tween upper and lower portions thereof, said door having therein a window opening which is provided with an inclined forward edge, a win- 95 dow having a forward edge which is curved, and metal guide runs mounted to have resiliency along their longitudinal dimension for so guiding said window in a curved path during the raising and lowering movement thereof as to render said window effective substantially to obviate uncov- 95 ering any portion of said forward window end.

2. A window organization for a car door having a forward end disposed at an obtuse angle be- 100 tween upper and lower portions thereof, said door having therein a window opening which is 105 provided with an inclined forward end, a window for closing said opening having a leading edge which is curved, channels for guiding said win- 110 dow in a curved path during raising and lower- 115 ing movement thereof, and means for supporting said channels to have them substantially re- 120 silient along their longitudinal dimensions.

3. In a window organization for a car door whose forward edge includes an obtuse angle 110 between upper and lower portions thereof, said door having therein a window opening which is 115 provided with an inclined forward edge, a win- 120 dow for closing said opening, means resilient 125 guiding said window in a curved path during the raising and lowering along its longitudinal dimension for movement thereof, and regulating means for maintaining the window horizontal during its movement.

4. In a car door having an angle in its forward edge, the upper portion of which is rearwardly inclined, said door having a window opening 120 whose forward edge is similarly inclined, a win- 125 dow for closing said opening, members for guid- 130 ing said window, and means for supporting one of said members so as to be substantially re- 135 silient longitudinally of its length.

5. In a car door having an angle in its for- 130 ward edge the upper portion of which is rear- 135 wardly inclined, said door having a window open- 140 ing whose forward edge is similarly inclined, a window for closing said opening, arcuate chan- 145 nel members for guiding said window, and means for supporting at least one of said channel mem- 150 bers so as to be substantially resilient longitudi- 155 nally of its length.

TRYGVE VIGMOSAD.

CERTIFICATE OF CORRECTION.

Patent No. 1,938,199.

December 5, 1933.

TRYGVE VIGMOSAD.

It is hereby certified that error appears in the printed specification of the above numbered patent requiring correction as follows: Page 2, lines 115 and 116, claim 3, strike out the words "along its longitudinal dimension for" and insert the same after "resilient" in line 113, of same claim; and that the said Letters Patent should be read with this correction therein that the same may conform to the record of the case in the Patent Office.

Signed and sealed this 9th day of January, A. D. 1934.

F. M. Hopkins

Acting Commissioner of Patents.
